UNITED STATES PATENT OFFICE

JOSEPH SLEPIAN, OF PITTSBURGH, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed April 6, 1927. Serial No. 181,289.

My invention relates to circuit breakers and particularly to arc-extinguishing devices thereof.

One object of my invention is to provide means for interrupting the flow of electricity 5 through gaseous media.

Another object of my invention is the provision of a circuit breaker provided with an arc-interrupting device capable of opening 10 high-voltage, large-current arcs in air or gas without recourse to oil or other arc-quenching media. Some of the aspects of my invention, are, however, applicable in connection with low-power, circuit-opening devices, and 15 to a variety of other uses.

The principal field for immediate application of my invention is in connection with alternating-current circuit breakers, and I shall hereinafter describe an embodiment of my 20 invention as applied to such circuit breakers, without in any way intending to restrict the scope of my invention, except as indicated in the appended claims.

According to the invention, the arc incident 25 to the opening of a circuit is driven into an endless arc track and maintained in continuous movement on said track until the arc has been extinguished. In order to extinguish the arc, the track is made in the form 30 of a chamber having deionizing surfaces in close proximity to the arc, and preferably sub-dividing the latter into serially related arc sections. By continuously driving the arc along said surfaces, they are maintained 35 relatively cool and protected from injury, notwithstanding the high arc temperature.

An unusually great deionizing effect is thus obtained which ensures prompt interruption of large-current, high-voltage arcs such as 40 could not satisfactorily be opened with commercial structures heretofore known to the art.

The features of the invention which I believe to be new are particularly pointed out 45 in the appended claims. For a full understanding of the principles of the invention, and the best mode of applying the same, reference may be had to the accompanying drawings, in which

Fig. 7 is a side view, partly in elevation and partly in section, of the deionizing structure.

The present invention is, in some aspects, 65 a further development of the circuit breaker described in my copending application Serial No. 54,930, filed Sept. 8, 1925, and assigned to the assignee of the present application.

In the foregoing application, I have shown 70 that large-power, high-voltage, alternating-current circuits may be opened without recourse to oil or other arc-quenching media, by introducing into the arc, conducting sheets 75 or nuclei so distributed in the arc space as to quickly deionize the same during the short interval in which the arc current is nearly zero. If the rate of deionization of the arc space is sufficiently large, as compared with 80 the rate of rise of voltage across the arc terminals after the current zero, a deionizing structure of the foregoing character will 85 safely prevent arc reignition after the current zero.

The deionizing structure described in the above-mentioned application had the form 90 of a chamber in which a plurality of reticulated sheets of conducting material, such as brass, were closely spaced, transversely to the arc. The arc was thus, everywhere and in all parts, close to portions of these conducting sheets.

Practical tests, and theoretical considerations set forth in the above mentioned application, indicate that the rate at which 95 the arc space is deionized depends directly on the number of sheets disposed in a given arc space and the intimacy with which said sheets embrace said space, inasmuch as the 100

deionization proceeds from the cathode terminal surface of the arc chamber and from the surfaces of the sheets facing in the same direction as the cathode terminal surface of the chamber.

5 On the cathode side of each sheet, a region that is nearly denuded of ions is formed, this region growing in thickness toward the next adjacent sheet until the entire spaces between the sheets are deionized. It is because of this deionizing action of the metallic portions of the individual sheets, which is similar to the deionizing action taking place near the cathode proper, that I often term the deionizing sheets or grids "artificial cathodes".

10 In the above identified application, it was also pointed out that the rate of the deionization of the space between the individual sheets of the deionizing chamber is the greater, the 15 more uniformly the arc space is filled with the deionizing sheets. That is, for most rapid deionization, it is desirable that the individual sheets which extend across the arc shall be solid and that the arc shall be broken up into short arcs which are individually confined between such solid metal sheets.

20 Although the desirability of having solid sheets was fully recognized in said prior application, practical tests showed that, with 25 the magnetic blow out structures then available, no successful arc de-ionizing structure for commercial circuit breakers could be developed with solid sheets, inasmuch as the serially disposed short arc sections into which 30 the arc would be divided by the sheets would form hot-cathode spots on the closely spaced deionizing sheets, melting the metal and producing metal vapor which is less easily deionized than air.

35 40 In addition, the melting of the metal would very soon weld the sheets together and render the entire structure inoperative. On the other hand, the close spacing between the deionizing sheets is very essential to a satisfactory operation on high-current, high-voltage circuits if the rate of deionization of the 45 arc space is to be made sufficiently large to permit the construction of a circuit breaker that can take over the duties now performed 50 by oil-circuit breakers and the like.

55 As an additional limitation, the speed of the movement of the arc within the deionizing structure had to be relatively low on account of the limited length of the arc chute possible in commercial breakers; with too great arc speed, the arc would be blown from the deionizing structure and would hang at the ends thereof, with entire loss of the deionizing effect of the structure.

60 As a result, the deionizing structure described in the foregoing application was, to a certain extent, a compromise between the requirement for solid deionizing sheets to 65 increase the rate of deionization of the arc

space and the requirement to provide a structure which will not require the arc to be split up into many small serially connected independent arcs, with separate cathode and anode terminals for each of the short arcs.

70 These contradictory requirements were solved by making the sheets with perforations of sufficient size to permit the arc to play freely through them as if there were no sheets placed across the arc. That is, the 75 deionizing structure of my former application introduced the metallic deionizing sheets into the arc space in order to provide "artificial cathodes" at the time the arc current was passing through zero, but, at other times, 80 as far as the arc was concerned, it aimed to leave the arc undisturbed in its movement, so far as possible, and permitted it to play between the main arc terminals of the chute, as if no such sheets were there.

85 The choice of perforated sheets with a view to avoiding development of hot-arc terminals on the individual sheets seemed also to be required from the generally known theories of arc operation, as understood until 90 recently. It did not seem possible that hot-cathode spots on the grid sheets could be avoided if there were to be a splitting up of the arc into separate arc-sections, with distinct cathode and anode terminals on the individual solid sheets.

95 Heretofore, it has been generally accepted that, in order to maintain an arc, that is, a self-maintaining discharge having a voltage drop at the cathode which is very considerably less than the normal glow discharge cathode drop for the particular cathode material in the given gas medium, there must exist a cathode having a temperature high enough to emit electrons. Such temperature 100 is higher than the melting temperature of the materials available for structures here in question, and would, accordingly be destructive to such structures.

105 Thus, as late as in 1923, K. T. Compton 110 presented, in the Physical Review, volume 21, page 226, etc., the result of a very thorough investigation of the nature of arc discharges, reaching the conclusion that the greater part 115 of the current carried at the cathode consists of thermionically emitted electrons.

120 However, as a result of experiments and studies, I have been led to the belief that thermionically active cathodes are not absolutely necessary for the maintenance of an arc discharge, and that, while frequently, arc discharges operate with hot cathodes, it is also possible to maintain an arc discharge under conditions where the cathode is cold, or, in any case, where the cathode has a temperature much below the temperature of electron emission.

125 Theoretical considerations, which are set forth in the Physical Review for April, 1926, pages 407-412, and theoretical analysis 130

show that it is possible to explain the characteristics of an arc maintained with a cold cathode by assuming that the passage of current from the arc to the cathode is obtained by thermal ionization in a gas layer next to the cathode, instead of by thermionic electron supply from the cathode.

An arc with a cold cathode, such as I have described above, may be obtained by causing the arc to move so rapidly over an extended cathode surface, that no point of the cathode surface is subjected to the heat of the arc for a time long enough to acquire a high temperature. When such an arc is obtained experimentally with copper electrodes, examination of the trace on the electrode surfaces shows that the current density there is very much greater than for an arc with a hot cathode.

Thus, I have found the current density with cold-cathode arcs to be about 30,000 amperes per cm^2 , whereas, for example, the usual carbon arc has a current density of only a few hundred amperes per cm^2 . This very high current density seems to be required by theory also, because, to maintain a layer of air immediately adjacent to the cold cathode at a temperature high enough for thermal ionization, that is, at a temperature of several thousand degrees centigrade, requires a very large input of power there, and this may be obtained by a very high current density.

According to the present invention, the fact that an arc may be maintained without producing hot-cathode spots on the arc electrodes is made use of in order to provide a deionizing structure in which the arc incident to the opening of a circuit is driven between solid metallic sheets and is split up into small arc sections with distinct cathode and anode terminals, the arcs between the individual sheets being maintained in the form which I designated before as "cold-cathode arc discharges".

Thus, the effectiveness of the deionizing structure used in circuit breakers of the type described in my foregoing application is greatly increased by making full use of the very large deionizing effect obtained with solid plates closely spaced transversely to the arc and maintaining the short arc discharges between said sheets in the form of "cold arc discharges", as explained above. That is to say, irrespectively of whether my present understanding and explanation of the "cold arc discharges" is correct, I provide a structure in which I sub-divide the arc incident to the opening of the circuit into a large number of small serially-connected arc sections playing in thin spaces between solid metal or conducting sheets without any considerable heating of said sheets and positively preventing melting or other injury to the sheets by reason of hot-cathode spots, or the like.

I have found that, if the arcs between the individual sheets are moved over the sheets with sufficient rapidity, there is no melting at the arc terminals and, presumably, the arc-current carriers are supplied entirely by thermal ionization of the air next to the cathode and between the sheets.

With arc-blow-out structures heretofore employed, the speed with which the arc could be moved between the arc electrodes was limited by the fact that, within the time available for the arc movement, that is, 1/120 of a second, in case of 60-cycle alternating current, the arc must remain confined between the de-ionizing sheets. If the arc was to be given a speed at which it could be maintained without heating the cathode, the prior arc-blow-out structure would require a length considerably beyond what was practically possible.

In an effort to obtain an arc-blow-out structure in which the speed of the arc movement would be free from limitation with regard to the length of the arc chute, and thus to make possible arc speeds at which the formation of hot-cathode spots on the electrodes should be avoided, I have devised a new type of arc-driving, or arc-blowing, arrangement which causes the arc to move over a limited area at such high speeds as are required to give the arc the necessary characteristics.

The new arc-driving arrangement is based on the idea of producing a peculiarly shaped magnetic field which causes the arc to keep on moving at very high velocity repeatedly over the same path in a limited space to which the arc is intended to be confined, the high arc velocity preventing excessive heating of the arc-terminal surfaces and the adjacent bodies so that the arc takes the form which I have termed "cold-cathode arc".

The novel arc-driving arrangement is not limited in its utility to deionizing structures of the type using closely-spaced deionizing sheets disposed transversely to the arc, but it has opened a large number of possibilities in improving other types of electrical apparatus, and particularly switching apparatus utilizing other kinds of arc or current-interrupting structures. Some of the claims appended hereto are, accordingly, directed to the features of the new arc-drive structure, irrespective of the type of apparatus in which it is utilized.

The diagrammatic illustration of the principal elements of a circuit breaker embodying my invention, as shown in Figs. 1 to 7, will make the novel features explained hereinabove readily understood.

The circuit breaker shown in the drawing has the usual main contact members 1 and 2 arranged to be bridged by a main contact brush 3 that is held on a main contact arm 4. The arm 4 is pivoted to swing the brush 3 between the position in which it closes the

circuit between the main contact members 1 and 2 and a position away from said contact members in which the circuit breaker is open.

The circuit breaker is further provided with an arc-interrupting structure 5 comprising an arcing contact arm 6 having, at its upper end, an arcing contact shoe 7 adapted to engage a stationary arcing contact member 8 for finally interrupting the circuit, the arcing shoe 7 and the stationary arcing contact member 8 being suitably connected, as by means of conductors 9 and 10 that include main blow-out windings 11, in parallel to the main contact members 1 and 2.

15 To open the circuit, the main contact arm 4 and the arcing contact arm 6 are swung to the right by means of a suitable toggle mechanism comprising a bell-crank lever, that is pivoted at 12, and links 13 so arranged that, 20 in opening the circuit breaker, the brush 3 is first lifted from the contact members 1 and 2, diverting the current from the brush into the shunting circuit through the arcing contact arm 6, arcing contact shoe 7, stationary contact member 8, conductors 9 and 10, and blow-out winding 11. Further movement of the bell-crank lever fully opens the circuit by swinging arm 6 to the right, thus bringing about disengagement of the arcing contact shoe 7 and the stationary arcing contact member 8 at their arcing tips 14.

A pair of auxiliary contact members 15, that are arranged to be opened somewhat later than the main contact members 1, 2 and 3, but somewhat earlier than the arcing-contact tips 14, are usually also provided to relieve the main contact members of arcing incident to the transfer of the current from the main brush 3 to the inductive shunt circuit including the blow-out coil 11 and the arcing contact members 7 and 8. Contact arm 4 is connected, near its hinge, to contact member 2 through the previously mentioned flexible connector 9 to complete a path 45 through contacts 14 from contact member 1 to contact member 2.

The arc-extinguishing structure, to which my invention is principally directed, comprises an arc-chute 21 which extends above the space where the arc between tips 14 of the arcing contact members 7 and 8 is drawn. The arc-chute comprises a pair of horn-like inclined arcing plates 22 and 23 to which the arc drawn between the arcing tips 14 of the 55 arcing contact members is transferred by means of a main blow-out magnet. The blow-out magnet comprises a laminated core 24 that is excited by the previously-mentioned blow-out winding 11 and a pair of pole shoes 60 25 positioned on opposite sides of the arcing horn plates 22 and 23. The upper ends of the inclined arcing horn plates 22 and 23 merge into vertical arcing plates 26 and 27, shown in detail in Fig. 2.

65 The pole shoe 25 and the vertical arcing

plates 26 and 27 thus define a straight rectangular chamber 28 having, at its lower end, a downwardly tapered arc-entrance chamber 29 extending between the inclined arc-horn plates 22 and 23 and the lower portions of the pole shoes 25. The magnetic flux induced between the pole shoes 25 has a direction transverse to the plane of the drawing so that, when the circuit breaker is opened and an arc is drawn between the arcing tips 14, the arc is blown toward the inclined arcing horn plates 22, 23, and then upwardly along the latter through the entrance chamber until it reaches the straight portion of the arcing chamber 28.

The straight portion of the arcing chamber between the arcing plates 26 and 27 is filled with a plurality of solid metallic sheets or plates 31 which I have before designated as the deionizing sheets or grids of the arc-interrupting structure. The individual sheets are insulated from each other, as by means of paper strips at the edges of the sheets; I have, however, omitted these from Fig. 1 of the drawing which indicates only the air spaces between the sheets.

The circuit-breaker elements, described so far, resemble, in every respect, the elements of the circuit breaker described in the above-identified prior application, except that, in the present case, the deionizing sheets filling the arc chamber between the vertical terminal plates 26 and 27 are solid instead of perforated. Other very important distinctions in respect to the differences of the 100 design of the two types of deionizing structure will be discussed later on.

Extending directly above the straight portion 28 of the deionizing structure, and as a direct continuation thereof, a circular extension 32 is provided into which the arc from the straight portion 28 of the deionizing structure is driven and wherein it is caused to travel along a closed path 33 around the center of the circular extension. When viewed from the side of Fig. 1, the deionizing sheets are as shown in Fig. 3.

In the practical construction of this type of circuit breaker, I make the vertical end plates 26 and 27 of the arc chamber in the form shown in Fig. 2 of the drawing, with a lower straight portion 34 merging into a circular portion 35 at the top thereof. The individual deionizing sheets 31, which are disposed within the space between the end plates 26 and 27, have also a lower straight portion and an upper circular extension, as shown in Fig. 3.

While the straight portion of each of the end plates 26 and 27 is solid throughout its 125 entire breadth, the straight portions of the intermediate deionizing sheets 31 have tapered slots 36 which are wide at the bottom and narrow down toward the top, each slot terminating at a point. I shall later explain 130

the reasons for providing the tapered slots in the individual deionizing sheets. The circular portions of the end plates 26 and 27 and of the individual sheets 31 of the deionizing chamber have central holes or openings 37. The sheets 31 have narrow radial slots 38 in their circular portions, for reasons which will be explained later.

Assuming that the arc current, in the structure of Fig. 1 of the drawing, flows in the direction from the left to the right, as indicated by the circle having a cross in Fig. 3, the field in the lower straight portion of the deionizing chamber must have a direction as indicated by arrows 39 in Fig. 3, in order to drive the arc upwardly along the straight portion 41 of the arc path.

After the arc reaches the circular part of the deionizing structure, I cause it to travel along the closed circular path 33 by providing a radial magnetic field, indicated by the arrows 42.

Since a magnetic field transverse to an electric arc always moves the arc in a path normal to the lines of force composing that field, this radial field causes the arcs between the plates of the deionizing structure to travel around it continuously in a circular path as long as such arcs remain in existence. The radial field 42 is obtained by means of suitable exciting coils arranged at intervals between the sheets to give a field of the required shape and strength, in a manner now to be explained.

In the arrangement shown in Fig. 1, there are two main groups of deionizing sheets 43 and 44, each group consisting of nine P-shape sheets. Between the left hand sheet of group 43 and the left-hand arc-terminal plate 27, is provided a radial field coil 45 which is connected between the terminal plate 27 and the nearest deionizing sheet of the group 43. With the current in the coil 45 flowing in the direction indicated by the arrow, a radial magnetic field will be produced in the narrow spaces between the deionizing sheets of the group 43, the dotted lines 46 indicating the direction and distribution in space of this flux. In order to provide a radial field of relatively great strength without requiring an excessive number of ampere turns in the exciting coils 45, I provide a plurality of washers 47 of magnetic material along the return path of this radial magnetic flux.

In order to provide the radial field between the five right-hand sheets of the deionizing group 43, I connect, between the right-hand sheet of said group and the left-hand sheet of the other deionizing group 44, a pair of oppositely wound coils 48 and 49 for inducing, in the spaces between the respective sheets, the radial fluxes, as indicated by the dotted flux lines 51 and 52. Magnetic washers 53 between the coils 48 and 49 provide low-re-

luctance magnetic return paths for the fluxes induced by said coils.

A coil 54, disposed to the right of the deionizing group which is connected in the same manner as the left hand coil 45 and which is similarly associated with a set of magnetic washers 55, provides for the radial flux in the right-hand portion of the deionizing group 44.

As shown in Fig. 3, the plates 31 have radial slots 38 which prevent their annular portions from acting as short circuited turns to damp out the magnetic field due to the coils 45, 48, 49 and 54.

In the portions of the deionizing chamber where the circular portion of the structure is occupied by the exciting coils 45, 48, 49 and 54 and the associated magnetic washers 47, 53 and 55, the deionizing sheets consist of only the straight lower extensions 61 shown in Fig. 4 of the drawings. Three sections 62, 63, and 64 of such short grids are provided in the structure below these three sets of circular field exciting coils and washers.

The structure of my circuit interrupter has now been described sufficiently to make clear its operation in extinguishing arcs.

It will be clear, upon a moment's consideration, that the tapered slots in the grids 31 and 61 aline, when assembled into a deionizing unit as above described, to form a groove in the resulting structure which may be roughly described as of V-shape. The reason for providing this V-shape groove will now be explained:

The high current density existing in a "cold-cathode" arc must be considered when it is attempted to cause, as I do in my invention, a long arc with low current density to be broken up into a series of short "cold-cathode" arcs. The following experiment illustrates the properties of an arc which I use in accomplishing this. If a cold wire is plunged into an unconfined arc which is playing out into the open, with only a low current density, and if the wire is given a negative electric potential with respect to the arc, only a small current of the order of a few milliamperes per cm^2 . will flow to the wire so long as it is cold, even though the wire is given a potential of several hundred volts relative to the arc. This is because the density of ionization in the arc is so low that the current carried to the cold wire is insufficient to raise the temperature of the air next to the wire to a temperature high enough for sufficiently intense thermal ionization to make the wire function as a "cold-cathode" arc terminal.

If, however, the arc into which the wire is thrust, is confined to a restricted hole or slot, so that its current density is high, then the application of a negative potential of only 30 volts will cause a very large current to flow to the wire while it is still cold. This is be-

cause, with the high density of ionization, the more intense current which flows to the wire causes the air next to the wire to be ionized thermally with sufficient intensity for a "cold-cathode" arc to form there.

It has already been stated that the production of cold-cathode arcs, as the means of transferring the current path to the "deion" structure, requires that the arc current shall be concentrated in an extremely small cross-sectional area. One object of the V-shape groove is to bring about this condition.

As the arc is driven upwards from the end strips 22 and 23 above-described by the field of magnet 24, its current flows through a relatively large cross section at comparatively low current density therein. The wide mouth at the base of the V-shape groove permits this arc to enter without difficulty. As the magnetic field forces the arc upward, the V-shape groove gradually contracts the cross-sectional area of the conductive path of the arc, this effect being due, probably, to the deionizing effect of the metal strips constituting the side walls of the groove. As the cross-sectional area of the arc is thus gradually constricted, while it is being blown upward, the current density therein becomes greater and greater. The potential gradient of the arc rises at the same time. In consequence of this, by the time the arc has been forced to the apex of the V-shape groove, the current flow therein has been highly concentrated, and the voltage gradient has become sufficient to force the arc to transfer to the narrow gaps between the deionizing plates.

I have found that, by properly proportioning the taper of the groove relative to the current to be interrupted, the arc may be made to transfer readily to the plates of the deionizing structure and there to operate as a series of cold-cathode arcs kept in motion by such means as the magnetic field herein described.

This increase of current density and of voltage gradient has obviously been gradual throughout the movement of the arc up the tapering groove, and the arc is, therefore, caused to break up into a series of short arcs running between the deionizing plates, smoothly and without any abrupt transition in its electrical condition. Not only does this avoidance of an abrupt transition facilitate the transfer of the arc to the cold-cathode mode of operation, but it is of great value by virtue of the fact that it also minimizes electrical disturbances and the production of transients on the circuits on which current flow is being interrupted.

Tracing, in detail, the steps in the process of arc interruption in my circuit breaker, the movement of the brush member 3 to the right interrupts the direct contact between members 1 and 2 and causes current to flow through winding 11 of the blowout magnet

24 to end plate 27, thence through arcing contacts 7 and 8 to contact arm 6 and conductor 9. As the contact arm 6 moves farther to the right, an arc is drawn between contacts 7 and 8. The arc is driven upward by the influence of the magnetic field between pole faces 25, the terminals of the arc transferring to the horns 22, 23, until it reaches the mouth of the V-shape groove in the deionizing structure 28. The arc continues to rise under the application of this magnetic field, and the tapering groove gradually constricts the cross section of the arc, simultaneously increasing its voltage gradient, as has already been described.

By the time the arc has reached the apex of the V-shaped groove, the density of ionization has been raised by the resulting current concentration to such a degree that the currents which flow to the metal plates are great enough to cause thermal ionization of the gas adjacent to the cold metal plates. Under these conditions, the cold-cathode discharge, which I have previously described, becomes possible between the plates 31 of the deionized structure 28, and the arc readily transfers, under the influence of the magnetic field, to the space between the plates above the apex of the V-shape groove.

While rising under the impulse of the magnet 24, along the straight portion of the chute, the arc sections in the plate groups 62, 63, 64, are shunted by the low-resistance coils 45, 48, 49, 54, so that the current diverts from these arc sections into the coils. By the time the arc has reached the top of the straight portion of the chute, the current in the arc sections 62, 63, 64 has reduced to zero, the coils 45, 48, 49, 54 carrying all the current and producing the radial magnetic field which drives the remaining arc sections around and around the circular portion of the chute.

During all the time that the arc is in contact with the metal plates of the deionizing structure, energy, in the form of heat, is being rapidly abstracted from it. Because of the rapidity with which the arc traverses the metal plates, no one spot on these ever becomes heated to a sufficiently high degree to emit an appreciable number of electrons or to melt.

It is readily seen from what has been said above that, in a deionizing structure comprising merely a series of metal plates, without the tapered slots which I have provided, theory and experiment indicate that the transition of the arc from its initial continuous condition into a series of cold-cathode arcs between metal plates would be difficult, and, in many cases, practically impossible. Such has in fact been found to be the case and, for many purposes, deionizing structures, without such V-shape grooves as I have described, are so ineffective as to be wholly

inoperative for the purposes they are required to serve. The presence of the groove is, therefore, a material addition to my invention and the explanation of its function as given above, is believed to be correct, but, independent of its correctness, experience has proved beyond question the much greater effectiveness in practice of deionizing structures provided with such grooves.

It will also be noted that the increase of arc current density resulting from the constricting effect of the walls of the V-shape groove has a further effect in forcing the transition of the arc from the single continuous form to the series of short arcs operating between the deionizing plates. The deflecting force which a given magnetic field exerts upon the air at any point is proportional to the current density at that point, so that constriction of the arc in the groove causes the force on the air in which the arc is playing to be greatly intensified and thus to carry the arc between the metal plates.

The contour to be given to the tapering slots above described in the deionizing plates depends upon many factors, such as the amount of current to be interrupted, the strength of the blowout magnet and the dynamics of air flow in the structure. In general, we may say that the taper must be sufficiently gradual. At each stage in the motion of the arc in the slot, the alternative is presented to it of standing still and being subjected to the blast of air due to the action of the magnetic field, or of moving with the air and being subjected to the increased constriction of the slot. Either alternative causes its voltage to be raised and, evidently, it will follow that alternative which will give the least rise in voltage. The slot should, therefore, be so designed that the rise in voltage in the arc due to the increasing taper is less than the rise in voltage which would be produced if the arc stood still and was subjected to the air blast produced by the magnetic field. In a circuit breaker rated to interrupt 10,000 amperes at 2500 volts on a 60 cycle circuit, for example, a slot which doubles in width for every one half inch of length has been found to be effective.

As to the proportioning of my deionizing structure, I have found that there should be such a number of gaps between the deionizing plates that not more than 300 volts should be impressed across each gap when the full line potential appears across the terminals of the open breaker.

The reason for this limitation is that it has been found that, in the absence of any other intense source of ionization, as the air gap between a pair of plate terminals is decreased from a value of, say, a centimeter, the voltage necessary to cause unlimited spontaneous ionization or breakdown of the intervening gap decreases until a certain mini-

mum is reached. A further decrease of the gap is found to cause an increase of the voltage necessary to cause breakdown. This minimum voltage is in the neighborhood of 300 volts for air with copper electrodes, the gap at which this minimum voltage occurs being less than 1/1000 of an inch at atmospheric temperature and pressure.

After the alternating current in the arc in the deionizing chamber has fallen to zero, in the course of the alternating current wave, thermal generation of ions ceases almost at once, due to the rapid cooling of the gas. The ions which are present at that time, however, disappear only slowly by recombination. The reversed electric field which springs up moves these ions into the solid deionizing plates, so that the deionization is thereby accelerated. This deionization does not become complete simultaneously throughout the space, but the layer next to the new cathode first becomes completely deionized, layers adjacent thereto still retaining a considerable degree of ionization.

For the very small currents necessary to initiate rupture of a spark gap, the layers of air which are still ionized may be considered as part of the electrode plates, and the layer throughout which deionization has become complete becomes the real insulating medium under break-down stress. If this layer is thinner than that corresponding to the minimum break-down voltage above-mentioned, the presence of that voltage across the adjacent electrode plates is naturally incapable of causing a new rupture in that deionizing layer, no matter how thin it may be. On the other hand, if this layer has become thicker than the gap corresponding to minimum break-down voltage, the voltage on the electrode plates is likewise incapable of causing its rupture. The worst possible condition would be that occurring at the instant of time when the completely deionized layer is of exactly the thickness corresponding to a minimum breakdown voltage in air. Therefore, under the worst conditions, rupture will not occur if the voltage on each path of adjacent plates is less than the minimum value of 300 volts above-mentioned. In actual practice, to allow a factor of safety and provide for possible effects of line surges, I provide one gap for each 100 to 200 r. m. s. volts of line potential.

Another way of explaining this 300 volt limit, one which agrees with the above theory, is to use the well known experimental fact that, in the absence of a hot cathode, or (as I have now shown we must also say) a hot layer of gas next to the cathode, an electrical discharge takes the form of a glow, which requires at least 300 volts to be maintained for the case of copper electrodes in air.

With further regard to the design of the deionizing structure, it may be said that the

deionizing effect is, in general, greater the greater the number of plates. Economy of space, therefore, calls for as close a spacing of plates as possible. On the other hand, considerations of mechanical rigidity, difficulties of manufacture and the danger of foreign substances finding lodgment between the plates and bridging the gaps, set a limitation on the closeness with which the plates may be spaced. One-sixteenth of an inch has been chosen as a compromise between these conflicting requirements.

As to the thickness of plates, it should be so chosen that the heat stored in the plates in an operation of the switch shall not raise their temperature unduly. Calculations show that it is only a thin skin of metal on the surface of each plate that can be effective in absorbing heat each time the arc passes a given point, so that thickness of plate has little influence on the speed which it is necessary to give the arc to prevent melting of the plates. Here again mechanical and manufacturing considerations are really the controlling factor in determining the selection of a thickness of one-sixteenth of an inch for the plates. Good heat conductivity and a high specific heat are important in fixing the permissible smallest speed of the arc, and so lead to the use of copper as a good material for the plates.

Immediately after the current in the arc reaches zero, if the arc does not reignite, the voltage across the switch rises to the instantaneous value of the generated voltage in a very short time. This time is the natural period of oscillation of the supply circuit, and, for ordinary generators, transformers, etc., is a few hundred-thousandths of a second. During this time, the voltage across successive pairs of deionizing plates must remain less than 300 if the arc is not to reignite there, as has been explained before. Hence, if the number of plates is such that the generated voltage divided by the number of plates is 100 to 200 volts r. m. s., a great degree of uniformity is required in the distribution of the impressed voltage among the series of plates. It is evident that the series of deionizing plates constitutes a series of condensers, with the line voltage impressed between its outside terminal members. An uneven distribution of this voltage among the various condensers may cause more than 300 volts to be impressed upon one pair of plates during the deionizing period, with consequent reignition of the arc there, thus throwing an increased gradient on the remaining members, so that, in this way, throughout the whole series the arcs between plates may reignite under a voltage which would have been insufficient to cause reignition if it had been distributed in a uniform manner.

It can be shown that the electrostatic capacity between plates and from plates to

ground, in a simple series of uniformly sized and spaced plates, causes an uneven voltage distribution. To eliminate this effect and use the plates at their maximum voltage efficiency, electrostatic shielding may be resorted to. Thus, 70, 71, 72, 73, 74 and 75 in Fig. 1 show a shield of a type which makes the voltage distribution more uniform. The shield comprises conducting sheets enveloping the deionizing structure and insulated from it by its casing.

It will be seen that the conducting sheets intercept the lines of electric force which would otherwise extend from the grid plates to neighboring objects at ground potential. The component of charging current corresponding to an electric field extending to ground is thus replaced by one corresponding only to the electric field between the plates 31 and the conducting sheets just mentioned. The potential of the latter is determined by their mutual capacities and the capacities between them and various plates 31. Thus, the sheets 73, 74 and 75 act as successive plates of a series of condensers influenced by the voltage existing between end plates 26 and 27. By a proportioning which will be clear to those skilled in the art, the plate 73 may be made to take a potential not far from the mean value at the potentials to which the plates 31 which it covers are charged; plate 74 to have nearly the means of the potentials of plates 31 near the middle of the deionizing structure; and sheets 75 to have nearly the mean of the potentials of plates 31 nearer end plate 26.

As a result of the small potential difference, the electric field between plates 31 and the sheets 73, 74 and 75 is relatively small, and the component of charging current corresponding thereto is likewise minimized. Since, as can be readily shown, it is this component of charging current which causes non-uniform distribution of the line voltage among the plates after extinction of the arc, the use of such shielding means eliminates uneven voltage distribution and the undesirable consequences thereof described above.

This solution of the problem presented by uneven potential distribution between the plates is not limited to a series of three shielding members denoted by 73, 74, and 75 but may be extended to comprise any desired number of elements where a higher line voltage or other conditions make it desirable to do so.

It will further be evident that this device is not limited in utility to the circuit interrupter here disclosed but may be applied to apparatus of other types.

The general mode of operation of my circuit breaker having now been described, certain practical details of construction shown in Figs. 5, 6, and 7 of the drawings will be

described. As previously stated, the deionizing plates 31 are assembled in units of 9 plates, each pair of plates being separated by annular washers of fish-paper, one washer separating the outer edges of the plates and the other washer separating the plates at their inner edges. At each side of each unit of 9 plates are assembled the magnetizing coils 45, 48, 49 and 54, while outside of these are the iron plates 47, 53 and 55 already described. As many sets of these units as are necessary, in consideration of the line voltage, are assembled on a cylindrical core 76 of some suitable insulating material, and an insulating plate 77 is provided at the rear. This whole assembly of plates, coils and washers is pressed firmly together into a rigid unit by means of through bolt 78 and insulating collars 79 and 81. This construction is clearly shown in Fig. 7. An insulating shell 82, containing the conducting sheets of the static shield 70-75, is arranged to enclose the sides of the entire unit and may extend beyond the end plate 26 for protective purposes.

The lower portion of the deionizing structure, comprising the deionizing plates 31 and 61 with their fish-paper separators and the end-plates 26, 27 and 77, are pressed firmly together by a pair of through bolts 83 acting thereon through spacing members 84, 85 and 86 of micarta. The sides of insulating shell are held firmly pressed against the edges of the fish-paper separators for the lower parts of plates 31 and 61 by spacing member 84 just mentioned. Fig. 6 makes this construction clear.

The lower portions 87 of the insulating shell extend down and form the side-walls of the chute or chamber in which the arc is drawn between arcing contacts 7 and 8, as previously described. To protect them from the heat of the arc, the side walls are lined with plates 88 of soapstone. The arc causes a slight vaporization of the metal of arc-shoe 7 and, to prevent the condensation of this metal from forming a continuous conducting coating across the face of the soapstone between arc horns 22 and 23, narrow deep grooves 89 are provided in the plates 88.

The arc horns 22 and 23 are bolted to plates 88 to form a unitary structure therewith, fitting snugly between the sides of shell 87, and supported therein by insulating spacers 90, the upper face of this structure abutting against the lower end of end plates 26 and 27, as Fig. 7 shows. Flexible connectors 91 and 92 electrically connect arc horns 22 and 23 with end plates 26 and 27.

The deionizing structure proper, thus constituted, is provided, on each side of the arcing chamber, with iron pole shoes 93 which fit tightly against the pole faces 25 of the core 24 of the blowout magnet. The blowout magnet is energized by the windings 11

which are insulated from the core by micarta collars 94. Windings 11 may obviously be positioned anywhere along the core 24. For the sake of clearness, the diagrammatic Fig. 1 shows the windings near the rear of the breaker; in the practical embodiment shown in Figs. 5, 6, and 7 they are shown nearer the front.

The entire deionizing structure thus constructed is supported, on the framework which supports the main contacts 1, 2 and the operating levers, by an insulator 95; and the lower parts of side plates 87 are bolted to a shoulder 96 on the main contact 1. The structure and details of the mechanism operating the main contacts may be in accordance with standard practice in circuit-breaker design and require no detailed description.

While, in accordance with the patent statutes, I have given the forgoing details of a practical embodiment of my invention, it is to be understood that many of these are merely illustrative and that variations of their precise form will be desirable in designing circuit breakers for other voltages and currents than those which I have specified above.

It will also be understood that many features which I have above described are adjunctive to each other, and that it is possible to provide circuit-interrupting means that shall be satisfactory for many purposes by the employment of only one of these various devices. Thus, while I provide the above-described V-shape groove in the deionizing structure which facilitates the transfer of the arc to the annular portion of the upper path of the deionizing chamber, it will be clear that the use of such an annular portion to deionize the arc is not dependent upon the presence of a V-shape groove. In many instances, it will be possible to cause the arc to transfer to operation between the deionizing plates, and to thus utilize the expedient of driving the arc about an annular path, even although no such V-shape groove is part of the device.

On the other hand, it will be clear that, for many purposes, it will be unnecessary to provide the annular path for the arc since a relatively short period of operation in the deionizing chamber may be sufficient to cause its extinction. Therefore, a structure in which the V-shape groove is present but in which no provision is made for an annular path for the arc would be within the purview of my invention. In fact, it is not essential that the plates forming the sides of the V-shape groove be integral with those constituting the annular path, and a structure embodying the V-shape groove but providing no path of operation for a sub-divided arc would still be within the scope of my invention.

The provision of electrostatic shielding for the deionizing structure is in no way confined to the particular shaping of the grid plates or to the presence of the V-shape groove, but is individually applicable wherever a series of deionizing plates is used, or wherever it is desirable that voltage stress be uniformized in a current interrupting device.

10 Also, the provision of the slots in the soap-stone walls of the chute is a valuable feature which co-operates with, but is not limited to, use in connection with the V-shape groove or the deionizing structure generally.

15 The principles which have been embodied in my circuit breaker are applicable to many other purposes than those of circuit interruption. I desire, therefore, that the language of the accompanying claims shall be 20 accorded the broadest reasonable construction and that my invention be limited only by what is explicitly stated in the claims and by the prior art.

I claim as my invention:

25 1. Circuit-interrupting means comprising a pair of members between which an arc may be drawn and deionizing means adjacent the arc path comprising a plurality of metal plates disposed to subdivide the arc into a series of short arcs and of such configuration as to provide a recurrent path for said short arcs.

30 2. Circuit-interrupting means comprising a pair of members between which an arc may be drawn, deionizing means adjacent the arc path comprising a series of metal plates arranged to subdivide the arc into a series of short arcs having such configuration as to provide a recurrent path for said short arcs and means to cause said short arcs to traverse said recurrent path.

35 3. Circuit-interrupting means comprising a pair of members between which an arc may be drawn, means to abstract energy from the sides of the arc, and means to confine the travel of said arc to a recurrent path.

40 4. Circuit-interrupting means comprising a pair of members between which an arc may be drawn, means adjacent to opposite sides 50 of the arc path to absorb energy therefrom, means to impel the arc into the space between said energy-absorbing means and deionizing means adjacent to the arc path comprising a plurality of metal plates disposed to subdivide the arc into a series of short arcs having such configuration as to provide a recurrent path for said short arcs.

45 5. Circuit-interrupting means comprising a pair of members between which an arc may be drawn, means adapted to deionize an arc when brought into contact therewith and means to confine the travel of said arc to a recurrent path adjacent said deionizing means.

50 6. Circuit-interrupting means comprising

a pair of members between which an arc may be drawn, means adapted to deionize an arc when brought into contact therewith, means to provide a recurrent path distinct from said members for said arc while in contact with said deionizing means and means to cause said arc to traverse said recurrent path.

7. Circuit-interrupting means comprising a pair of members between which an arc may be drawn, means to progressively constrict the arc, means to provide a recurrent path for said arc and means to cause said arc to traverse said recurrent path.

8. Circuit-interrupting means comprising a pair of members between which an arc may be drawn, a plurality of metal plates positioned in a portion of the arc path, means to provide a recurrent path for said arc and means to cause said arc to traverse said recurrent path.

9. Circuit-interrupting means comprising a pair of members between which an arc may be drawn, a plurality of metal plates positioned in a portion of the arc path, means to deflect said arc toward said metal plates, means to provide a recurrent path for said arc and means to cause said arc to traverse said recurrent path.

10. Circuit-interrupting means comprising a pair of members between which an arc may be drawn, a plurality of metal plates positioned in a portion of the arc path, means adapted to deionize an arc when brought into contact therewith, means adapted to provide a recurrent path for said arc and means to cause said arc to traverse said recurrent path.

11. Circuit-interrupting means comprising a pair of members between which an arc may be drawn, a plurality of metal plates positioned in a portion of the arc path and having notches tapering to an apex, means to deflect said arc toward said metal plates, means adapted to deionize an arc when brought into contact therewith, means to provide a recurrent path for said arc and means to cause said arc to traverse said recurrent path.

12. Circuit-interrupting means comprising a pair of members between which an arc may be drawn, means adjacent the sides of the arc path to absorb energy therefrom, means to impel the arc toward said energy-absorbing means, means adapted to deionize the arc when brought into contact therewith, means to provide a recurrent path separate from said members for said arc while in contact with said deionizing means and means to cause said arc to traverse said recurrent path.

13. Circuit-interrupting means comprising a pair of members between which an arc may be drawn, a structure comprising a series of spaced metal plates positioned in a portion of the arc path and having notches which taper to an apex to form a substantially V-shape groove in said structure, means to deflect the arc into said V-shape groove, said

- notches and said plates being so formed and spaced that when the arc is running in the apex of said groove, the density of ionization is so great as to make it capable of readily transferring to a cathode which is substantially not thermionically emissive, deionizing means adjacent the apex of said groove comprising a plurality of spaced conducting plates disposed to subdivide the arc into a series of short arcs, and of such configuration as to provide a recurrent path for said short arcs and means to cause said short arcs to traverse said recurrent path.
14. Circuit-interrupting means comprising a pair of members between which an arc may be drawn, a structure comprising a plurality of spaced conducting plates positioned in a portion of the arc path and having notches tapering to an apex to form a substantially V-shape groove in said structure, means to deflect the arc into said V-shape groove, one or more separate deionizing units adjacent the apex of said groove, each comprising a plurality of spaced conducting plates disposed to subdivide the arc into a series of short arcs and of such configuration as to provide recurrent paths for said short arcs, and windings connected in series with said separate units and disposed to set up magnetic fields at right angles to said recurrent paths.
15. Circuit-interrupting means comprising a pair of members between which an arc may be drawn, a structure comprising a plurality of spaced conducting plates positioned in a portion of the arc path and having notches tapering to an apex to form a substantially V-shape groove in said structure, means to deflect the arc into said V-shape groove, one or more separate deionizing units adjacent the apex of said groove, each unit comprising a plurality of spaced substantially P-shape conducting plates disposed to sub-divide the arc into a series of short arcs and of such configuration as to provide recurrent paths for said short arcs, and windings connected in series with said separate units to set up magnetic fields along radii of said recurrent paths.
16. Circuit-interrupting means comprising a pair of members between which an arc may be drawn, a structure comprising a plurality of spaced conducting plates positioned in a portion of the arc path and having notches tapering to an apex to form a substantially V-shape groove in said structure, means to deflect the arc into said V-shape groove, one or more separate deionizing units adjacent the apex of said groove, each unit comprising a plurality of spaced plates not over one-eighth of an inch thick, and spaced not over one-eighth of an inch apart, dis-
- posed to subdivide the arc into a series of short arcs and of such configuration as to provide recurrent paths for said short arcs, windings at each end of each deionizing unit connected in series with said separate units and so disposed as to set up magnetic fields at right angles to said recurrent paths, and magnetic return paths for the flux of said fields between said deionizing units.
17. Circuit-interrupting means comprising a pair of members between which an arc may be drawn, a structure comprising a plurality of spaced conducting plates positioned in a portion of the arc path and having notches tapering to an apex to form a substantially V-shape groove in said structure, means to deflect the arc to said V-shape groove, a deionizing structure comprising a plurality of substantially P-shape conducting plates, and means to cause said arc to traverse an annular path through said P-shape plates.
18. Circuit-interrupting means comprising a pair of separable contact members between which an arc may be drawn, a structure comprising a plurality of conducting plates positioned in a portion of the arc path and having notches tapering to an apex to form a substantially V-shape groove in said structure, means to deflect the arc into said V-shape groove, one or more separate deionizing units adjacent the apex of said groove, each unit comprising a plurality of spaced substantially P-shape conducting plates disposed to sub-divide the arc into a series of short arcs and of such configuration as to provide recurrent paths for said short arcs, and windings connected in series with said separate units to set up magnetic fields along radii of said recurrent paths.
19. Circuit-interrupting means comprising a pair of members between which an arc may be drawn, means to progressively constrict said arc, deionizing means positioned to intercept said arc as it recedes comprising a plurality of spaced conducting plates transverse to the arc path, means to provide a recurrent path for said arc and means to cause said arc to traverse said recurrent path.
20. Circuit-interrupting means comprising a pair of separable contact members between which an arc may be drawn, arcing horns positioned to receive said arc from said contact members, means to progressively constrict said arc as it lengthens between said horns, means to progressively increase the potential gradient of said arc as it recedes from said horns and deionizing means positioned to intercept said arc as it recedes comprising a plurality of spaced conducting plates transverse to the arc path, means to provide a recurrent path for said arc and means to cause said arc to traverse said recurrent path.
21. Circuit-interrupting means comprising

- 5 a pair of members between which an arc may be drawn, a structure comprising a plurality of spaced conducting plates adjacent the arc path and having notches tapering to an apex to form a substantially V-shape groove in said structure, a magnet to be energized when said arc is drawn and positioned to deflect said arc into said V-shape groove, one or more separate deionizing units alined with the apex of said groove, each unit comprising a plurality of spaced conducting P-shape plates to sub-divide the arc into a series of short arcs, and windings connected in series with said separate units to set up magnetic fields tending to drive said short arcs in a recurrent path about the loop of each P-shape member.
22. Circuit-interrupting means comprising a pair of separable contact members between which an arc may be drawn, a structure comprising a plurality of spaced conducting plates adjacent to the arc path and having notches tapering to an apex to form a substantially V-shape groove in said structure, a magnet to be energized when said arc is drawn and serving to deflect said arc into said V-shape groove, one or more separate deionizing units alined with the apex of said groove, each unit comprising a series of conducting P-shape plates, spaced not over one-eighth of an inch apart to subdivide the arc into a series of short arcs, and windings connected in series with said separate units to set up magnetic fields tending to drive said short arcs in a recurrent path about the loop of each P-shape member.
23. Circuit-interrupting means comprising a pair of members between which an arc may be drawn, deionizing means comprising a plurality of spaced conducting plates positioned to intercept said arc and means to cause a uniform distribution of potential differences among said plates when the arc current is substantially zero.
- 45 24. Circuit-interrupting means comprising a pair of members between which an arc may be drawn, deionizing means comprising a plurality of conducting plates spaced not over one-eighth of an inch apart and positioned to intercept said arc, and means to cause a uniform distribution of potential differences among said plates when the arc is extinct.
- 55 25. Circuit-interrupting means comprising a pair of members between which an arc may be drawn, deionizing means comprising a series of spaced conducting plates positioned to intercept said arc and of such configuration as to provide a recurrent path for said arc, means to cause said arc to traverse said recurrent path and means to cause a uniform distribution of potential differences among said plates when the arc is extinct.
- 60 26. In combination with a source of alternating electromotive force, a circuit-interrupting means comprising a pair of members be-

tween which an arc may be drawn, deionizing means adjacent the arc path comprising a plurality of metal plates to subdivide the arc into a series of short arcs and of such configuration as to provide a recurrent path for said short arcs, and means to cause said short arcs to traverse said recurrent path, the arrangement of said plates being such that the potential difference between a pair of plates never exceeds three hundred volts.

27. Circuit-interrupting means comprising a pair of separable contact-members between which an arc may be drawn, a deionizing chamber having insulating side walls which is substantially enclosed and means for transferring the arc to said chamber.

28. A method of extinguishing an electric arc which comprises the steps of abstracting energy through the sides of the arc, subdividing the arc into a series of shorter arcs and causing said arcs to traverse a recurrent path.

29. A method of extinguishing an electric arc which comprises the steps of subdividing the arc into a series of shorter arcs and causing said arcs to traverse a recurrent path.

30. A method of extinguishing an electric arc which comprises the steps of increasing the density of ionization in said arc, subdividing said arc into a plurality of cold-cathode arcs and causing said arcs to traverse a recurrent path.

31. Electric discharge means comprising a plurality of spaced metallic plates and means to cause an arc between said plates to traverse a recurrent path thereover.

32. An electric discharge device comprising a metallic electrode and means to cause an arc to traverse a recurrent path upon said electrode at such velocity that substantially no vaporization of said electrode occurs.

33. In combination with a source of alternating electromotive force, circuit-interrupting means comprising a pair of members between which an arc may be drawn, deionizing means adjacent the arc path comprising a plurality of metal plates arranged to subdivide the arc into a series of short arcs of such configuration as to provide a recurrent path for said short arcs, and means to cause said short arcs to traverse said recurrent path, the arrangement of said plates being such that the potential difference between a pair of plates never exceeds that necessary to produce a glow discharge.

34. In combination with a source of alternating electromotive force, circuit-interrupting means comprising a pair of members between which an arc may be drawn, deionizing means adjacent the arc path comprising a series of metal plates arranged to subdivide the arc into a series of short arcs of such configuration as to provide a recurrent path for said short arcs, and means to cause said short arcs to traverse said recurrent

path, the number of said plates being approximately equal to the voltage of the source divided by the normal cathode drop of the material of which said plates are made.

5 35. Circuit-interrupting means comprising a pair of members between which an arc may be drawn, and means for causing a substantially uniform distribution of electric potential over the path of the arc immediately after extinction of the arc.

10 36. Circuit-interrupting means comprising means for establishing an arc, a structure comprising spaced conducting plates positioned in a portion of the arc path and of such configuration as to provide a recurrent path for said arc, windings disposed to set up magnetic fields perpendicular to said arc path and means to impede the induction of currents in said plates by changes of current 15 in said windings.

20 37. Circuit-interrupting means comprising means for establishing an arc, a plurality of conducting plates positioned in a portion of the arc path and having notches tapering to 25 an apex, said notches halving in width in every longitudinal distance of from one-tenth to two inches, means adapted to deionize an arc when brought into contact therewith, means to provide a recurrent path for said 30 arc and means to cause said arc to traverse said recurrent path.

35 38. Circuit-interrupting means comprising means for establishing an arc, a plurality of spaced conducting plates positioned in a path traversed by said arc and means for causing a substantially uniform distribution of electric potential among said plates after interruption of the arc.

40 39. In combination with a source of alternating electromotive force, circuit-interrupting means comprising a pair of members between which an arc may be drawn, means adapted to deionize an arc when brought into contact therewith and means to confine the 45 travel of said arc to a recurrent path adjacent said deionizing means.

40 40. The method of maintaining an electrical arc which consists in moving said arc over a recurrent path so rapidly that neither 50 electrode emits a substantial number of electrons.

45 41. The method of interrupting the flow of current in an electric circuit which comprises opening a pair of separable contacts traversed by said current, transferring the resulting arc to a recurrent path distinct from said contacts and moving the arc so rapidly about said path that no electrons are emitted from said path.

50 In testimony whereof, I have hereunto subscribed my name this 28th day of March, 1927.

JOSEPH SLEPIAN.
